(57) **CLAIM**

The ornamental design for a paint can shaking saw attachment, as shown and described.

DESCRIPTION

FIG. 1 is a perspective view of a paint can shaking saw attachment, showing my new design;

FIG. 2 is a rear elevational view thereof;

FIG. 3 is a left-side elevational view thereof, the right-side elevational view being a mirror image thereof;

FIG. 4 is a top plan view thereof;

FIG. 5 is a right-side elevational view thereof; and,

FIG. 6 is a left-side elevational view thereof.

The broken lines showing a paint can, strap and reciprical saw in FIG. 1 depict environmental matter and form no part of the claimed design.
